UNITED STATES PATENT OFFICE.

JOHN J. HAHN, OF KANSAS CITY, MISSOURI, ASSIGNOR OF ONE-THIRD TO
GEORGE B. ALLEN, OF KANSAS CITY, KANSAS.

SHADE-GUIDE.

SPECIFICATION forming part of Letters Patent No. 536,517, dated March 26, 1895.

Application filed June 28, 1994. Serial No. 516,014. (No model.)

To all whom it may concern:

Be it known that I, JOHN J. HAHN, of Kansas City, in the county of Jackson and State of Missouri, have invented certain new and useful Improvements in Curtain-Fixtures; and I do hereby declare that the following is a full, clear, and exact description of the invention, which will enable others skilled in the art to which it appertains to make and use the same, reference being had to the accompanying drawings, and to the letters of reference marked thereon, which form part of this specification.

This invention relates to certain improvements in curtains for car or other windows.

The object of the invention is to provide improved means for confining and guiding the vertical edges of the curtain, and to provide improved means for securing the curtain and for moving the same.

The invention consists in certain novel features of construction and in combinations of parts more fully and particularly described hereinafter and pointed out in the claims.

Referring to the accompanying drawings: Figure 1, is an elevation of the curtain taken from the interior of the car. Fig. 2, is a cross sectional view on the line 2—2, Fig. 1. Fig. 3 shows in perspective one of the hooked heads and also the device for attaching the curtain thereto detached from the head and curtain. Fig. 4, is a detailed elevation of one edge of the curtain detached from the hooked head, showing the tab and fastening device thereon which slips into the hooked head, dotted lines showing the hem at the edge of the curtain. Fig. 5 is a detail elevation of a portion of the curtain, looking at the opposite side to that seen in Fig. 4, and showing the hooked head and cross bar thereof, dotted lines showing the hem at the edge of the curtain.

In the drawings, *a*, is the curtain. This curtain can be mounted on a suitable spring roller, if desired, or other means can be employed for operating the curtain.

Suitable means, such as guides, can be provided for the vertical edges of the curtain and the curtain is secured to means extending into and confined in said guides. In the present instance where the curtain is shown

applied to a summer car, the vertical guides *b*, are secured to the sides of the posts or uprights *c*, arranged at the ends of the car seats and supporting the roof. The curtain is 55 adapted to close the space between these uprights or posts.

Each guide way is preferably composed of a tube having the lateral flange *d*, by which it is secured to the upright so that the inner 60 edge of the tube is located a short distance from the edge of the upright. This inner edge of the tube next to said flange is provided with a longitudinal slot *e*. The guide ways are longitudinally secured on the uprights usually throughout the entire length thereof traversed by the curtain. Each guide way can be suitably bent or otherwise formed from a single piece of metal.

The lower edge of the curtain is provided 70 with a rigid cross bar *f*, forming a handle. The curtain is secured on this cross bar.

The ends of the cross bar can be formed of metal and hooked or U-shaped in cross section, see *h*, so as to partially embrace the guide 75 tube and fit between the same and the upright *c*, and extend through the slot into the tube so that both ends of the cross bar of the curtain are confined to slide on said guide ways and extend into the same.

The inner end or edge of each head *h*, within the guide can have a vertical opening *i*. The vertical edges of the curtain are formed with heavy hems *j*. At the lower end of the curtain these hems are separated from the 85 body of the curtain for a short distance by vertical slits, thus leaving the lower ends of the hems at the bottom corners of the curtain free to form tabs or tapes *k*. Each tab is provided with a metal binding strip *l*, longitudinally arranged on the outer edge thereof. Each metal binding strip is preferably composed of a strip of U-shaped sheet metal clamped on a tab and then inserted through the opening *i*, in the inner end of the hook *h*. 95

The curtain is secured in the heads of the cross bar by means of these metal binding strips on the tabs. Each strip is clamped within the hook *h*, in any suitable manner as by having its lower end bent or expanded so 100 as to prevent its pulling out of the head when downward strain is exerted.

The upper portion of the binding and clamping strip l , is provided with a hook l' , above the hook h , and parallel therewith to act as a guide for the curtain. The curtain 5 extends into the groove over the outer face of the hooks. The hems at the edges of the curtain are thus confined within the guide way and a slot in the guide way is preferably so narrow as to prevent the edges of the curtain 10 pulling out because of the thick hems.

The curtain covers one side of the guide way and passes between the cross bar head and the guide way so that the edge of the curtain is confined to the guide way during 15 the vertical movement of the curtain and the cross bar holds it firmly in place and yet permits free and easy vertical movement therein.

o , is a stop secured to the upper portion of each guide way and extends into the path of 20 the cross bar so as to prevent the cross bar heads moving out of the confined guide way.

By means of the metal binding strip the curtains can be easily attached to the hooked heads of the cross bars and can be detached 25 therefrom when necessary.

It is evident that various changes might be made in the forms, arrangements and constructions of the parts described, without departing from the spirit and scope of my invention. Hence I do not wish to limit myself to 30 the exact construction herein set forth, but consider myself entitled to all such changes as fall within the spirit and scope of my invention.

Having thus fully described my invention, 35 what I claim as new, and desire to secure by Letters Patent of the United States, is—

1. In combination, vertical supports, the inclosing guide tubes thereon having the lateral 40 flanges supporting the inner face of the tube a distance from the support, said inner face of the tube toward the support having the longitudinal slot, the vertically movable curtain at its edges partially embracing said 45 tubes and provided with the edge enlarge-

ments or hems confined therein, and the hooked heads at or about the lower end of the curtain and partially embracing the exterior of said tubes and extending to the interior thereof and having the curtain secured 50 thereto, substantially as described.

2. The vertical supports, and the inclosing guide tubes secured thereto having their inner longitudinally slotted faces held a distance from the sides of the supports, as described, so that the longitudinal slot into each tube is through the side of the tube farthest from the other tube, in combination with the vertically movable curtain between said tubes and fitting the exteriors thereof and extending around the same through said slots with its longitudinal edges confined in the tubes, and heads traveling and confined in said tubes, and to which the lower portions of the curtain are secured, substantially as described. 60

3. The combination of vertical inclosing guide tubes, the curtain, the hook shaped traveling heads attached to the lower portion of the curtain and confined in said tubes, and the metal binding strips secured on the lower 70 portions of the edges of said curtain within the tubes and secured to said heads within the tubes, substantially as described.

4. The combination of the slotted guide tubes, the vertically movable curtain, the 75 cross bar of the curtain having the hooked ends confined in said tubes with the openings in their inner ends in the tubes, and the metal strips in the tubes and confined in said openings and secured on the lower portions of the 80 curtain edges, said strips provided with the guides l' at their upper ends, as set forth.

In testimony that I claim the foregoing as my own I affix my signature in presence of two witnesses.

JOHN J. HAHN.
